UNITED STATES PATENT OFFICE.

GUILFORD C. BABCOCK, OF EVANSTON, ILLINOIS, ASSIGNOR TO WIREBOUNDS PATENTS COMPANY, OF KITTERY, MAINE, A CORPORATION OF MAINE.

BOX.

Specification of Letters Patent. Patented Sept. 18, 1917.

1,240,297.

Application filed August 5, 1914. Serial No. 855,275.

To all whom it may concern:

Be it known that I, GUILFORD C. BABCOCK, a citizen of the United States, residing in Evanston, Cook county, Illinois, have invented an Improvement in Boxes, of which the following description, in connection with the accompanying drawings, is a specification, like characters on the drawings representing like parts.

This invention relates to boxes and the like and is intended to provide a novel construction of box blank and box and a method of making the same.

Among other objects, the invention is intended to provide a box which shall be simple and economical to manufacture; which shall be susceptible of manufacture upon automatic or partly automatic machinery; and which in the finished box shall be strong and durable and preferably tight.

For the purpose of illustration the invention will be described herein as embodied in, and employed in the manufacture of, a sectional box having oppositely disposed cleat-side sections and additional side sections which are not cleated and which may be disconnected from the structure of the box except as they are held in place by the frictional grip of their parts.

The character of the invention will be readily understood by reference to the accompanying drawings in which Figure 1. is a side or edge elevation of an illustrative form of box blank.

Fig. 2. is a perspective view of the illustrative blank partly folded.

Fig. 3. is an end view of the finished box.

The box blank comprises side sheets 1 and 2 conveniently of gum veneer, having respective cleats 3 and 4 of suitable wood. Wire binding 5 or the like, preferably in a continuous length, is secured to the side sections, as by staples 6, 6 straddling the wires, passing through the side sheets 1 and 2, and penetrating the cleats 3 and 4.

When the blank comprising the side sections 1 and 2, is folded together, the cleats 3 and 4 substantially contact lengthwise as shown in Fig. 3.

To provide additional sides of the box loose strips 7, 8 may be employed and these are preferably of comparatively heavy stock to serve as stiffening or strengthening members. Strips 7 are indicated by dotted lines

in Fig. 1 to show the relations which they would have to the remaining parts of the blank preparatory to folding. As shown in Fig. 3 the strips 7, 8 are embraced between overlapping margins of the side sheets 1 and 2, these overlap margins being indicated at 9, 10, 11 and 12 in Fig. 1. Preferably these overlap margins have widths substantially equal to the thicknesses of the strips 7 to be overlapped thereby. The edges of the side sheets 1 and 2 in the specific type of blank shown in Fig. 1 are spaced apart a sufficient distance to receive between them the strip 7 and to permit the parts to be folded into the overlapping relation shown in Fig. 3. In order to tension the wire binding over the corners of the box and thereby assist in holding the strips 7 in place, it is preferred that the space between adjacent edges of the sheets 1 and 2 be somewhat greater than the width of the strip 7 but less than the width of said strip 7 plus the combined thicknesses of the sheets 1 and 2. This arrangement requires the wires to be put under tension as the parts are folded into the positions of Fig. 3 and in such tensioning the wires may be forced to embed themselves more or less in the corners, likewise when the free ends 13, 13 of the binding wires are twisted or otherwise secured together to complete the closure of the box they may tension the wires over the corners adjacent the stiffening strip 8.

The box of the drawing is desirably flexible and elastic and may be considerably distorted without material tendency to rupture its parts, since the distorting strains are resisted largely by the tensile strength of the wire.

One practicable method of making a box such as that described is as follows: A pair of side sheets 1 and 2 of the same dimensions are assembled with cleats 3 and 4 of the same dimensions. The side sheets are spaced apart edgewise a distance slightly greater than the combined widths of the cleats 3 and 4; and the cleats are spaced apart edgewise a distance substantially equal to the space between the side sheets plus a distance equal to double the thickness of the strip 7 which is intended to be interposed between the sides 1 and 2. These relative positions provide for the overlap margins 10 and 11 and for tensioning wires over the

corners. Similar overlap margins 9 and 12 are left at the outer ends of the side sheets 1 and 2.

A blank such as we describe the parts of 5 which are of uniform size, is very simple and economical to manufacture and when continuous lengths of binding wires are used side sections of the type described may be assembled with appropriate spacing devices and fed rapidly through a stapling machine which secures the wires to the parts in any practicable manner.

Then when the blank is ready for folding into box form loose strips 7, 8 may be 15 properly inserted and then when the box is folded around the strips so placed, the wires may be tensioned to hold the strips in position. If desired one more additional fastening means such as the nails 15, 16, 17 and 20 18, employed as shown in Fig. 3 or in any other practicable manner, may be utilized.

It is to be understood that this invention is not limited to the particular construction, organization and method of manufacture 25 hereinbefore described for illustration. On the contrary, the relations of the box parts and the materials therefor may be modified in form and dimensions and the method of making the box modified in various particulars all of which will appear to those skilled 30 in the art. Furthermore, it is not indispensable that all the features of the invention be used conjointly since they may be employed separately in the combinations 35 and sub-combinations defined in the following claims.

It is to be understood further that the words "box", "ends", "sides", and similar words are employed herein as words of convenient designation and not words of limitation since obviously the features of the invention may be applied to other receptacles and containers than those ordinarily described by the word box (and which are intended to be included under that name as herein used); and it is immaterial what particular part of a box is employed in any given instance as its end or side.

Claims:

50 1. A box comprising, in combination, ends including each a pair of cleats substantially contacting lengthwise with each other; un-

cleated side strips extending across the ends of said cleats; side material on the sides of said cleats and extending across the edges 55 of said side strips; and means for securing the parts together.

2. A box comprising, in combination, oppositely disposed side sections, having end cleats between them and substantially closing the box end, and having also overlap margins projecting beyond the ends of said cleats; and non-cleated side strips between said overlap margins.

3. A method of making wirebound boxes 65 which consists in assembling separate sections of side material with separate sectional cleats, each cleat and its side material being relatively positioned to provide overlap margins projecting beyond the cleat ends; spacing apart edgewise the sections so formed to accommodate side pieces between said overlap margins; foldably connecting the sections by flexible binding with the cleats 70 arranged to mate in the folded box substantially to close the box ends.

4. A box comprising, in combination, oppositely disposed side sections, having end cleats between them which substantially close the box ends and also having overlap 80 margins projecting beyond the ends of the cleat material, non-cleated side strips between said overlap margins and wires encircling the ends of the box and secured by fastening means passing through said side 85 sections into the cleats.

5. A box comprising, in combination, oppositely disposed side sections, having end cleats between them which substantially close the box ends and also having overlap 90 margins projecting beyond the ends of the cleat material, non-cleated side strips between said overlap margins, fastening devices securing said margins to said side strips and wires encircling the ends of the 95 box and secured by fastening means passing through said side sections into the cleats.

In testimony whereof, I have signed my name to this specification, in the presence of two subscribing witnesses.

GUILFORD C. BABCOCK.
